UNITED STATES PATENT OFFICE.

ROBERT FRANKLIN SNOW, OF ELBA, ALABAMA.

DESIGN FOR A LAMP.

49,297.

Specification for Design.

Patented July 4, 1916.

Application filed January 21, 1916. Serial No. 73,472. Term of patent 7 years.

To all whom it may concern:

Be it known that I, ROBERT FRANKLIN SNOW, a citizen of the United States, residing at Elba, in the county of Coffee and State of Alabama, have invented a new, original, and ornamental Design for Lamps, of which the following is a specification, reference being had to the accompanying drawing, forming a part thereof.

Figure 1 is a perspective view; and Fig. 2 is a side elevation of a lamp, showing my new design.

I claim:

The ornamental design for a lamp, as shown.

ROBERT FRANKLIN SNOW.
